COMBINED BOTTLE AND DISPLAY CARTON THEREFOR

Charles H. Berman, 2405 Braeburn,
Flossmoor, Ill. 60422

Filed Mar. 20, 1972, Ser. No. 236,552

Term of patent 14 years

Int. Cl. D9—01
U.S. Cl. D9—12

Fig. 1.

Fig. 2

Fig. 3.

FIG. 1 is an isometric view of a combined bottle and display carton therefor showing my new design;

FIG. 2 is an isometric view showing the bottom and side opposite that seen in FIG. 1; and

FIG. 3 is an elevational view thereof.

I claim:

The ornamental design for a combined bottle and display carton therefor, as shown.
